(57) **CLAIM**

The ornamental design for a drawer front panel, as shown and described.

DESCRIPTION

FIG. 1 is a front perspective view of a drawer front panel, showing a first embodiment of our new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is a rear perspective view thereof;

FIG. 9 is a front perspective view of a drawer front panel, showing a second embodiment of our new design;

FIG. 10 is a front view thereof;

FIG. 11 is a rear view thereof;

FIG. 12 is a left view thereof;

FIG. 13 is a right view thereof;

FIG. 14 is a top plan view thereof;

FIG. 15 is a bottom plan view thereof; and,

FIG. 16 is a rear perspective view thereof.

The drawer front panel is shown with a symbolic break in its width. The appearance of any portion of the article between the break lines forms no part of the claimed design.
